UNITED STATES PATENT OFFICE.

ARTHUR FOTY LA PIERRE, OF ST. LOUIS, MISSOURI.

DESIGN FOR A PHONOGRAPH-CABINET OR SIMILAR ARTICLE.

57,679.

Specification for Design. Patented Apr. 26, 1921.

Application filed November 8, 1919. Serial No. 336,755. Term of patent 3½ years.

To all whom it may concern:

Be it known that I, ARTHUR F. LA PIERRE, a subject of the King of Italy, residing in the city of St. Louis and State of Missouri, have invented a new, original, and ornamental Design for a Phonograph-Cabinet or Similar Article, of which the following is a specification, reference being had to the accompanying drawing, forming part thereof.

The figure is a front view of a phonograph cabinet or similar article showing my new design.

I claim:

The ornamental design for a phonograph cabinet or similar article, as shown.

ARTHUR FOTY LA PIERRE.
